JOHN A. WELTON, OF CANAL DOVER, OHIO.

APPARATUS FOR FEEDING FINE FUEL.

1,127,136.

Specification of Letters Patent.

Patented Feb. 2, 1915.

Application filed May 29, 1913. Serial No. 770,719.

To all whom it may concern:

Be it known that I, JOHN A. WELTON, a citizen of the United States, residing at Canal Dover, in the county of Tuscarawas and State of Ohio, have invented certain new and useful Improvements in Apparatus for Feeding Fine Fuel, of which the following is a specification.

This invention relates to certain new and 10 useful improvements in apparatus for feeding fine-fuel to furnaces and burning the same therein.

The apparatus comprises means for the initial reduction of the fuel; means for further reducing the fuel into fine and coarse 15 particles; means for feeding the coarse particles into the combustion chamber of a furnace where it will serve as a pilot fire; means for separating the fine particles from 20 the coarse particles and feeding said fine particles into the combustion chamber of the furnace where they may be burned in suspension or over the pilot fire of coarse fuel; means for regulating the feed of the material automatically by boiler conditions; 25 and means for supplying an adequate supply of oxygen to facilitate combustion of the fuel in the combustion chamber.

My invention further consists of the parts 30 and the constructions, arrangements and combination of parts which I will herein-after describe and claim.

In the accompanying drawings forming part of this specification and in which similar reference characters indicate like parts in the several views;—Figure 1 is a longitudinal sectional view of part of a boiler furnace and associated grinding mechanism embodying the salient features of my invention. Fig. 2 is a cross section of the fire box on the line 2—2 of Fig. 1, omitting the pressure regulating devices. Fig. 3 is a modification showing the grates upon which the pilot fire may be burned. Fig. 4 is a detail of the mechanism for regulating the action of the feed screw, 9. Fig. 5 is a cross sectional view through a grinding device of modified form.

In carrying out my invention I may use 50 the leading features thereof in connection with any well known and desired form of furnace. In the drawings I have illustrated my invention in connection with a locomotive boiler-furnace of any approved construction and which furnace has a combustion chamber, 1, to which access is afforded

through a fire-door, 2. The combustion chamber is operatively connected to a boiler, 3, and in the combustion chamber is arranged a curved fire-arch, 4, of refractory material and which arch may include a series of curved bars, or tubes, 5, one or both ends of which may be suitably connected to a union or other coupling, 6. The arch, 4, is composed of fire-brick or the like and in or through said arch is formed a series of openings or perforations, 7, through which a part of the products of combustion may escape to the space in rear of the arch, said arch terminating at its upper end short of the front wall of the combustion chamber so as to form a flue or passage for the greater portion of the products of combustion.

It will be understood that the fire-box 75 may have any desired form and its shell may be of any design and construction well known in the art, and that the furnace shown is but illustrative of any furnace with which the leading features of my invention may be operatively connected.

The aforesaid arch rises from the bottom of the rear end of the combustion chamber and extends in a curve forwardly of the direction of the front of said chamber, so 85 as to overhang the grate, or suitable twyers, the top of the arch being spaced from the top of the fire-box, so that the products of combustion may pass over the same to the rear end of the fire-box, and through the 90 same to the ordinary flues with which the boiler of the type of furnace shown will in practice be supplied. The arch extends throughout the entire width of the fire-box and is constructed of fire-brick or other refractory material, and it may have a construction similar to that which appears in my former Patent Number 993,928, dated May 30, 1911, without departing from the spirit of the present invention.

The lower portion of the fire-box casing is provided with a curved trough, 8, in which operates a screw conveyer, 9, adapted to feed fuel into the bottom of the combustion chamber for the purpose of serving as a pilot-fire, as I will hereinafter describe. The walls of the combustion chamber may also be lined with fire-brick, 10, or other refractory material as shown in Fig. 2, and in the lower portion of the combustion 110 chamber at each side of the center thereof, is a twyer, 11, which consists of a pipe

perforated in its upper portion and adapted to discharge air into or upon the bed of fuel in the combustion chamber, each of said twyers having one end opening through the bottom of the fire-box casing, as shown in Fig. 1, whereby any ashes filtering into the twyer through the perforations may be readily discharged; this discharge end of the twyer is provided with some suitable form of damper or valve, 12, by means of which the passage through the twyer may be opened and closed at will.

If desired, there may be used as a substitute for, or in addition to the twyers, the oppositely inclined grates, 13, as shown in Fig. 3, and upon which grates the aforesaid screw conveyer will discharge the coarser particles of fuel to be consumed thereon and to serve as a pilot-fire for other and finer particles of fuel fed into the combustion chamber above the grates and below the arch.

Operatively connected to the front portion of the furnace fire-box is an apparatus for reducing the fuel to such condition that it may be delivered into the combustion chamber of the furnace in such quantities and under such conditions as will promote complete combustion of the fuel and at the same time insure maximum heating properties. To this end, I construct a suitable casing, 14, with a hopper, 15, or like receiver for the coal or material to be crushed or ground; and to which hopper the coal may be conveyed or delivered in any manner and by any of the mechanisms commonly used in this art for the purpose, and in order to obtain the desired feed of this material to the crushing devices, I use some appropriate form of feed regulator, the character of which is unimportant, although I have shown in the present drawings for illustrative purposes a regulator in the form of a tubular damper, 16, which is supported above a horizontal rotatable disk, 17, having a raised or conical center for directing the material toward the edge of the disk and under the lower edge of the tubular damper, said disk being provided with a toothed surface, 18, adapted to be engaged by a beveled pinion, 19, mounted on a shaft, 20, journaled in the casing and operated by any well known means. The shaft carrying the pinion, 19, may have its outer end provided with a sprocket wheel, 21, while the opposite end carries a spur gear, 22, adapted to mesh with a similar gear, 23, on the shaft of the agitating roll, 24, which roll may be of any suitable character and if desired, provided with teeth or spikes, to more effectually act upon the material delivered to the roll from the feeding means above. Below the roll, 24, which I prefer to term the agitating roll, since the purpose of said roll is to agitate the material passing from the

feeding devices, is a crushing roll, 25, of any well known character suitable for my purpose, to which the coal is fed and by which it is crushed and fed forwardly to be further reduced by devices which I will presently describe. The crushing roll operates in the bottom of a crushing chamber and the bottom of this chamber is formed of a plate, 26, of sufficient strength to resist the crushing action of the roll, said plate being preferably yieldingly supported upon suitable springs, 27, and said plate having openings, 28, through it for the passage of material reduced by the roll and of sufficient size to readily pass through the perforations into a trough, 29, which is alined with and forms a part of a trough, 8, formed below the fire-box of the furnace and in which the screw conveyer, 9, operates, whereby the material passing through the perforated bottom of the crushing chamber and thereby separated from the balance of the material may be fed by the screw into the combustion chamber and onto or between the twyers or grates therein. This separated material may represent what I term the coarser particles of the fuel used by me and it is designed to serve as a pilot-fire upon and above which the finer material hereinafter mentioned will be burned.

The crushing roll, 25, may be operated by a sprocket chain, 32, running from the sprocket wheel, 21, to a pinion, 33, on the shaft of the crushing roll. The crushing roll may have spiral ribs or may have its periphery otherwise formed to insure the feeding of material longitudinally of the roll and to suitable pulverizing or reducing devices which I will now describe.

The casing, 34, in which the feed regulating means and the crushing devices before described, are mounted, is extended at one side and this casing is provided with suitable bearings for the opposite ends of the shaft, 35, which carries the crushing roll. The shaft, 35, is the main shaft of the apparatus and power is applied to it through the medium of a motor, 35', or other connection which may be of any desired well known type. On the shaft, 35, adjacent the crushing roll, is arranged a muller-wheel, 36, which is designed to act upon material fed by the roll into the chamber in which the muller-wheel operates and in which chamber this material is further reduced. The chamber has its wall provided with an opening, 37, through which some of the material reduced in the chamber by the muller-wheel will be permitted to escape into the trough in which the screw conveyer, 9, operates whereby this material may be fed by the screw into the combustion chamber with such other material as may have entered the screw from the initial crushing chamber, as before described. On the shaft, 35, I also fix-

edly secure a plurality of muller-wheels, 38, each of which is substantially of truncated form and each of which, as well as the muller-wheel, 36, has an open center or is otherwise 5 constructed to form a passage lengthwise of the shaft through which the fine material produced in the crushing chamber, either by the action of the crushing roll, or by the agitation of the roll, 24, will be drawn from 10 the crushing chamber through said passage and will be delivered pneumatically into the combustion chamber of the furnace. To this end the casing, in which the mullers operate is provided with a fan-chamber, 39, in which 15 a rotary fan, 40, of some appropriate form operates, to induce a draft from the initial crushing chamber through the open mullers so that the fine material picked up by the draft will be delivered from the casing into 20 the pipe, 41, and finally discharged into the combustion chamber of the furnace through the medium of a discharge head, 42, with which the pipe communicates, said discharge head being of any suitable character 25 and having as many branches as may be desired and one form of which is shown in my prior Patent No. 993,928, before mentioned.

Appropriately mounted in the horizontal 30 extension of the casing, 34, and surrounding each of the truncated formed mullers is a ring or annulus, 43, which may be substantially triangular in cross section, whereby its inner face substantially conforms to the inclination or taper of the periphery of the co-acting truncated formed muller-wheels.

In Fig. 1, I show the two muller-wheels, 38, as being relatively reversed and accordingly the ring or annulus, 43, which surrounds these muller-wheels, will be likewise 40 relatively reversed. The purpose of this construction is, that one of the muller-wheels will balance the other when under working conditions, since by reversing one muller-wheel relatively to the other, or reversing the angular position of the outer surface of the pair of muller-wheels, I am permitted to balance the pressure due to centrifugal force in the chamber in which the pair of 45 muller-wheels operate. I thus overcome the end thrust which would otherwise occur during the operation of the machine and I maintain the relation between the grinding surfaces of the mullers and their co-acting 50 rings or annulus so as to obtain the greatest grinding capacity with a minimum of resistance and horse power.

In addition to the fan and fan-casing heretofore described and which are employed for delivering the fine-fuel under pressure into the combustion chamber below the curved arch, I place alongside of the first-mentioned fan, a second fan, 44, which operates in a suitable case or chamber, into 55 which leads an inlet pipe, 45, which is valve-

controlled so that the volume of air drawn into the casing during the operation of the second fan may be regulated, said casing having discharge openings, 46, which communicate with the front ends of the twyers, 11, positioned in the lower part of the combustion chamber, it being understood that the casing, in which the second-named fan operates has two outlets, one of which communicates with each of the aforesaid perforated twyers, whereby air delivered from the second-named fan, will be discharged into the twyers under pressure, it being assumed that the outer ends of these twyers are closed, and air will be delivered through the perforations upon or through the bed of coarse fuel which may constitute a pilot-fire for the furnace.

Provision is made for the automatic operation of the foregoing devices, whereby the furnace fire is controlled according to the pressure in the boiler, the fuel supply being reduced when the boiler pressure rises above a predetermined point and being increased when the boiler pressure drops below said point, the pressure regulator being exposed to the action of the steam in the boiler and connections from the regulator control the fuel supply. This will be better understood by reference to Fig. 1, wherein the pressure regulator, 44', which may be of any suitable type, is located in the steam space of the boiler. The regulator is shown as provided with a rod or stem, 45', which extends longitudinally through a tube, 46', located in the upper portion of the furnace, said tube being open to the atmosphere at the outer end, and said rod, 45', extending through this open end and being connected to one arm of the bell-crank lever, 47, pivotally mounted on the front of the furnace shell, the other arm of said lever being provided with a series of holes, to any one of which may be pivotally connected the upper end of a rod, 48, whose lower end is likewise 105 adjustably pivotally connected to an arm, 49, of a lever, 50, which is pivoted at one end to a suitable bracket 51' and has its opposite portion slidably over a quadrant, 51. To this lever is also pivotally connected the upper end of a rod, 52, which is designed to extend to a crank-arm, 53, on a horizontal shaft, 54, and which shaft is provided with an eccentric, 55, from the strap of which extends a rod, 56. The arrangement and 110 operation of the foregoing parts are similar to what is shown and described in my prior Patent No. 993,929, dated May 30, 1911, and which specific features form no essential part of the present claimed invention.

On the shaft of the feed screw, 9, is fixedly secured a disk or wheel, 60, having ratchet teeth and on the said shaft is also pivotally connected a pitman, 61, Fig. 4, to the outer end of which is connected a 115 120 125 130

rod, 63, which in turn is connected to a crank, 64, on the outer end of the shaft of the agitating roll, 24, whereby the agitating roll and feed-screw are operated in unison. 5 The pitman, 61, is provided with a pivotal dog or pawl, 65, and to this dog is connected an arm, 66, which is provided with a curved slot, 67, through which passes a bolt, 68, whereby the arm may be adjusted to regulate the throw of the pawl or dog. On the shaft of the feed screw is also mounted a lever, 69, the lower end of which is pivotally connected by a link, 70, to the short arm 71, of a pivoted finger, 72, as shown in Fig. 4, 10 adapted to contact with an arm on the pawl for the purpose of disengaging the pawl during the operation of the hand lever, said lever having intermediate of its ends, an arm, 73, to which is connected the upper end 15 of the adjustable rod, 56, which is fixed to the strap of a suitable eccentric, 55, mounted on the shaft, 54, the said lever having its upper portion provided with an extension or handle, 76, pivotally mounted thereon, which 20 may operate over a curved segment or like part whereby the lever may be rocked and adjusted and held in any of its adjusted positions, to thereby fix the throw of the pawl or dog, 65, and the consequent rotation of 25 the feed screw. The operation of these parts is substantially as follows: The movement of the crank, 53, is transmitted to and actuates the lever, 69, which in turn actuates the finger, 72, the purpose of 30 which is to keep the pawl, 65, from contacting with the ratchet on the wheel, 60, when the boiler pressure is high. As the lever, 61, is operated through the rod, 63, and crank-arm, 64, it carries with it the pawl, 65, and 35 the slotted lever, 66, the levers, 61 and 66, and pawl, 65, being free to move up and down a distance equal to the throw of the crank, 64. As the lever, 61, is loosely mounted 40 relatively to the lever, 69, and as both are freely mounted on the shaft, 31, of the feed screw, it is quite evident that the movement 45 of lever, 61, cannot in any way interfere with the operation of the lever, 69, and vice versa. The lever or handle, 76, is pivotally mounted 50 on the upper portion of the lever, 69, and has a short arm, 76^a, adapted to bear down slightly on the end of the slotted arm, 66, to thereby disengage the pawl, 65, from the ratchet teeth on the wheel, 60, and stop the 55 operation of the feed screw, but without changing the air and fine coal supply. It is understood that the lever, 76, operates over the curved segment, 76^b, before mentioned, which is rigid with the lever, 69, so that as 60 the cam, or eccentric, 55, moves the lever, 69, the segment and the lever, or extension, 76, are carried with the aforesaid lever, 69. In other words, the lever, 69, with its arm, 73, and segment, 76^b, and the lever, 76, are so 65 connected that they will move in unison

about the shaft, 31, and during the rocking movement of the lever, 69, the finger, 72, is likewise moved to actuate the pawl, 65, in the manner before described.

In Fig. 5 I show a modified form of mechanism for feeding fuel to the grinding devices and wherein I employ suitable gates or plates which enter the casing from opposite sides and whose inner edges are adapted to approach and recede from each other to regulate the feed of the material from the receiving chamber, *a*, into the crushing chamber, *b*, said gates controlling the communication between these two chambers, and each of the gates being slidably mounted and being actuated by a screw shaft, *c*, having quick threads operating in a nut, *d*, said screw shaft being connected to a lever, *e*, to which is connected a link, *f*, which in turn is connected to an arm or link, *g*, on the shaft, *54*, this construction being substantially disclosed in my former application filed December 2, 1912, Serial Number 739,593, and is illustrative of a different type of feeding mechanism from that before disclosed.

The casing of the apparatus may also be provided with a shutter controlled opening, *t*, for the admission of suitable quantities of air into the grinding chamber between the agitating roll and the crushing roll, it being understood that the shutter or damper controlling said opening may be connected to the other parts of the apparatus in such manner that it may be automatically controlled to admit such quantities of air as will best promote the combustion of the fuel, and it being apparent that the finer fuel delivered through the crushing and muller chambers will be delivered into the furnace through the burner head by the action of the suction fan, and that the air inlet opening referred to provides for the proper draft through the apparatus for the purpose specified. I have also shown in the upper portion of the steam dome of the boiler a pressure regulator, 80, which may be of any well known character and from which a pipe, 52', may lead to any well known form of steam turbine, as for instance in the manner substantially as shown in my former Patent Number 993,929, dated May 30, 1911. Around the upper portion of the muller casing I may also provide a space, 81, forming a passageway for coarse particles of coal to escape from the initial muller chamber and thence to the feed screw, 9, where it may be conveyed by the latter into the furnace to be burned on the grate, or twyters, any suitable feeding devices being used in this space for the purpose mentioned, as may be desired.

From the foregoing description it will be understood that coarse coal may be fed into the crushing chamber in a state of agitation and will be crushed in this chamber, the

coarser particles passing directly into the presence of the feed screw and the finer particles in the form of dust being drawn through the apparatus and delivered through the pressure-head into the combustion chamber below the arch thereof; and that other portions of the fuel will be progressively ground while passing the millers to be eventually reduced to substantially 10 dust-like form and delivered through the burner-head as before described. I am thus permitted to provide a mechanism whereby coarse hard particles will be delivered to a feed screw or the like to be fed to a pilot fire on the grates or in the space between the twyers, while the finer fuel will be delivered into the combustion chamber above the pilot fire there to be burned in suspension. I do not have to reduce all of the coal to powder-like form and this results in a saving in the power required to operate the apparatus. The advantage in my construction over a regularly underfed fire is that where the dust is fed in over the pilot fire, all the heat 20 generated from the dust is produced without the accumulation of cinder and clinker; another advantage is that the air passing through the coal on the grates, or twyers, is heated and toned down before it impinges 25 on the brickwork or lining of the fire-box. The feed screw feeds the pilot fire but a comparatively small amount of coal, and as the greater portion of the heat is produced by the fine particles burned in suspension, it is evident that the clinker trouble 30 of the ordinary furnace is practically eliminated.

It will be understood that the foregoing features may be used in connection with such accessories and minor features of detail as would be commonly employed for the transmission and control of power from one part to another, without departing from the spirit of my invention. It will also be understood from the foregoing that when an engine is in a station or passing through a city or populous community, the feed screw, 31, can be stopped and the dust fire alone employed, which will practically eliminate the smoke emitted from the engine. In other words, the feed screw may be employed only at such times that the engine is called upon to do the maximum amount of work, when it may be necessary to start 45 the screw and feed some of the coarser fuel to assist the dust fire.

Having thus described my invention what I claim as new and desire to secure by Letters Patent is:—

60 1. In apparatus for feeding and burning fine fuel, the combination with a furnace having a combustion chamber and elements upon which a bed of fuel may be supported, of a crushing mechanism for initially reducing the fuel, means for separating the

coarse particles of fuel from the finer particles, a conveyer connecting with the fire-box of the furnace adapted to feed said coarse material into the presence of said bed supporting elements to form a pilot fire, 70 and pneumatic means connecting with the crushing chamber and combustion chamber of the furnace adapted to conduct the fine material into said combustion chamber where it is burned in suspension above said pilot fire. 75

2. In apparatus for feeding and burning fine fuel, the combination with a furnace having a combustion chamber and elements in the bottom thereof upon which a pilot fire may be burned, of a casing connecting with the furnace, fuel-feeding means within said casing, crushing elements within the casing adapted to reduce said material, said casing having means for separating the coarse particles of fuel from the finer particles, grinding elements succeeding the crushing elements adapted to further reduce the fine particles, means for inducing a draft through the casing and grinding elements, whereby the draft acts as a vehicle for carrying the fine material, said casing having a discharge conduit connecting with the furnace and adapted to deliver the fine material into the combustion chamber thereof, and a conveyer for delivering the separated coarse material into the combustion chamber to form a bed of pilot fire above which the fine material is burned in suspension. 90

3. In apparatus for feeding and burning fine fuel, the combination with a furnace having a combustion chamber and elements in the bottom thereof upon which a pilot fire may be burned, of a casing connecting with the furnace, fuel-feeding means within said casing, crushing elements within the casing adapted to reduce said material, said casing having means for separating the coarse particles of fuel from the finer particles, grinding elements succeeding the crushing elements adapted to further reduce the fine particles, means for inducing a draft through the casing and grinding elements, whereby the draft acts as a vehicle for carrying the fine material, said casing having a discharge conduit connecting with the furnace and adapted to deliver the fine material into the combustion chamber thereof, a conveyer for delivering the separated coarse material into the combustion chamber to form a bed of pilot fire above which the fine material is burned in suspension, and means for supplying air under pressure into the presence of said pilot fire. 105

4. In apparatus for feeding and burning fine fuel, the combination with a furnace having a combustion chamber and elements in the bottom thereof upon which a pilot fire may be burned, of a casing connecting 110

with the furnace, fuel feeding means within said casing, crushing elements within the casing adapted to reduce said material, said casing having means for separating the 5 coarse particles of fuel from the finer particles, grinding elements succeeding the crushing elements adapted to further reduce the fine particles, means for inducing a draft through the casing and grinding elements, whereby the draft acts as a vehicle for carrying the fine material, said casing having a discharge conduit connecting with the furnace and adapted to deliver the fine material into the combustion chamber there- 10 of, a conveyer for delivering the separated coarse material into the combustion chamber to form a bed of pilot fire above which the fine material is burned in suspension, and means connecting with the conveyer for 15 regulating the movement of the same and the feed of the coarse material to the pilot fire.

5. In apparatus for feeding and burning fine fuel, the combination with a furnace 25 having a combustion chamber and elements in the presence of which a pilot fire may be sustained, of a casing, fuel feeding means therein, means for agitating the fuel in the casing, grinding elements within the casing 30 adapted to reduce said material, means for separating by gravity, the coarser from the finer particles of the material, a pneumatic conveyer connecting with the interior of the casing adapted to serve as a carrier for the 35 fine material, said pneumatic conveyer adapted to deliver the fine material into the combustion chamber of the furnace, a conveyer for delivering the separated coarse particles of fuel into the combustion chamber 40 to supply a pilot fire therein, and means for operating the second-named conveyer to regulate the feed of the coarse material.

6. In apparatus for feeding and burning fine fuel, the combination with a furnace 45 having a combustion chamber and elements in the presence of which a pilot fire may be sustained, of a casing, fuel feeding means therein, means for agitating the fuel in the casing, grinding elements within the casing 50 adapted to reduce said material, means for separating by gravity the coarser from the finer particles of the material, a pneumatic conveyer connecting with the interior of the casing adapted to serve as a carrier for the 55 fine material, said pneumatic conveyer adapted to deliver the fine material into the combustion chamber of the furnace, a

conveyer for delivering the separated coarse particles of fuel into the combustion chamber to supply a pilot fire therein, and means 60 for regulating the feed of the coarse material.

7. In apparatus for feeding and burning fine fuel, the combination with a furnace having a combustion chamber and elements 65 in the present of which a pilot fire may be sustained, of a casing, fuel feeding means therein, means for agitating the fuel in the casing, grinding elements within the casing adapted to reduce said material, means for 70 separating by gravity the coarser from the finer particles of the material, a pneumatic conveyer connecting with the interior of the casing adapted to serve as a carrier for the fine material, said pneumatic conveyer 75 adapted to deliver the fine material into the combustion chamber of the furnace, a conveyer for delivering the separated coarse particles of fuel into the combustion chamber to supply a pilot fire therein, means for 80 operating the second-named conveyer to regulate the feed of the coarse material, and an air blower adapted to deliver air under pressure into the presence of the pilot fire.

8. In fuel feeding and burning apparatus, 85 the combination with a furnace having a combustion chamber, of a casing, fuel feeding means in said casing, crushing elements in the casing adapted to reduce the material, said casing having means for separating by 90 gravity the coarse from the fine particles of reduced material, a conveyer for delivering said coarse particles into the fire box to form a bed constituting a pilot fire, a pneumatic conveyer serving as a carrier for the fine material and adapted to deliver said material into the combustion chamber of the furnace where it is burned in suspension 95 above the pilot fire, means succeeding the crushing devices for further reducing the 100 material from which the finer particles have been removed, said pneumatic conveyer adapted to separate and deliver into the combustion chamber the fine particles as the grinding progresses, and an air blower connecting with the fire box adapted to blow air under pressure thereinto in the presence of the pilot fire.

In testimony whereof I affix my signature in presence of two witnesses.
